(57) **CLAIM**

I claim the ornamental design for a World Trade Center 9/11 building monument memorial lamp, substantially as shown and described.

DESCRIPTION

FIG. 1 is a perspective view of the World Trade Center 9/11 building monument memorial lamp of the invention.

FIG. 2 is a top view of the World Trade Center 9/11 building monument memorial lamp of the invention.

FIG. 3 is a bottom view of the World Trade Center 9/11 building monument memorial lamp of the invention.

FIG. 4 is a front view of the World Trade Center 9/11 building monument memorial lamp of the invention.

FIG. 5 is a right side view of the World Trade Center 9/11 building monument memorial lamp of the invention.

FIG. 6 is a left side view of the World Trade Center 9/11 building monument memorial lamp of the invention.

FIG. 7 is a rear view of the World Trade Center 9/11 building monument memorial lamp of the invention; and,

FIG. 8 is a perspective view of the World Trade Center 9/11 building monument memorial lamp of the invention similar to FIG. 1, shown with the September 11th position illuminated.

The simulative antenna is shown broken away in FIGS. 4, 5, 6 and 7 for convenience of illustration.
